[57] CLAIM

The ornamental design for a mop-wringing bucket, as shown and described.

DESCRIPTION

FIG. 1 is a top perspective view of a mop-wringing bucket, showing our new design;

FIG. 2 is a bottom perspective view thereof;

FIG. 3 is a sectional view thereof, taken along line 3—3 of FIG. 1;

FIG. 4 is a top perspective view of a second embodiment of a mop-wringing bucket;

FIG. 5 is a bottom perspective view thereof;

FIG. 6 is a sectional view thereof, taken along line 6—6 of FIG. 4;

FIG. 7 is an end elevational view thereof.

FIG. 1

FIG. 2

FIG. 3

FIG. 7

FIG. 4

FIG. 5

FIG. 6
